(57) **CLAIM**

The ornamental design for an air conditioner housing, as shown and described.

DESCRIPTION

FIG. 1 is a front left perspective view of an air conditioner housing in accordance with the present disclosure;

FIG. 2 is a front right perspective view of the air conditioner housing shown in FIG. 1;

FIG. 3 is a view of the air conditioner housing shown in FIG. 1 from the front;

FIG. 4 is a view of the air conditioner housing shown in FIG. 1 from the rear;

FIG. 5 is a view of the air conditioner housing shown in FIG. 1 from the left;

FIG. 6 is a view of the air conditioner housing shown in FIG. 1 from the right;

FIG. 7 is a view of the air conditioner housing shown in FIG. 1 from the top; and,

FIG. 8 is a view of the air conditioner housing shown in FIG. 1 from the bottom.

The broken lines in the figures show portions of the air conditioner housing that form no part of the claimed design.

1 Claim, 8 Drawing Sheets
